COLLAPSIBLE KITE

John F. Neary, North Wales, Pa.

Application November 25, 1933, Serial No. 699,772

1 Claim. (Cl. 244—22)

The present invention relates to an improved collapsible kite, wherein all parts of the kite, namely the kite skeleton, the tie cords for the kite sail remain associated intact, whether the kite skeleton is collapsed or extended in open position.

Another purpose is to provide, in a kite, a kite skeleton comprising a longitudinal stay and two sections of a transverse stay, there being a slide head on the longitudinal stay and having pivoted thereto the two sections of the transverse stay, whereby the two sections can be moved pivotally in position to hold the kite in an operative position, and by moving the slide head toward the smaller end of the kite, the sections of the transverse stay may be collapsed, as well as the sail of the kite, whereby the kite may be packed for storage or shipment.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawing and claimed.

In the drawing:—

Figure 1 is a view in perspective of the improved kite constructed in accordance with the invention, showing the kite open, therefore in an operative position.

Figure 2 is a sectional view on line 2—2 of Figure 1.

Referring to the drawing 1 identifies the longitudinal stay of the kite, on which a slide head 2 is mounted. This slide head is constructed from sheet metal, preferably stamped, though it may be otherwise formed, and pivoted at 3 to the ears of the slide head are two sections 4 of the transverse stay 5.

While the two sections of the transverse stay as well as the longitudinal stay may be constructed of any suitable material, for instance a light wood, they are preferably constructed of aluminum, in the form of small rods, which may be either round or grooved like umbrella stays. The slide head has a channel way 6 through which the longitudinal stay extends, so that the slide head may move longitudinally on the longitudinal stay. A stop pin or lug or the like 7 is carried by the longitudinal stay to limit the slide head in such

a position, when the kite is extended to an operative position, so as to hold the two sections of the transverse stay in transverse extended positions. The remote ends of the two sections of the transverse stay have eyes 8, while the remote ends of the longitudinal stay have eyes 9. Suitable cords, wires or the like 10 are connected to the eyes 8 and 9 by means of hooks 11. Engaged over the cords or wires are the folded edge portions 12 of the sail 13 of the kite, and which sail may be constructed of any suitable very light fabric, paper or other material, through which the air will not so readily pass. Preferably a kite fabric is designed to be used for the kite sail, so as to facilitate the collapse of the kite, though it is possible to construct the sail of paper such as will readily fold. Eyes 8a of the transverse stay are connected by a transverse cord or wire 14, which is taut sufficient to bow the sections of the transverse stay into the customary kite formation. Suitable eyes 15 are carried by the longitudinal stay, and to which a bridle cord 16 is connected. A suitable kite flying cord 17 is connected to the bridle cord, whereby the kite may be allowed to ascend when the flying cord is properly manipulated. It is easily obvious that by moving the slide head downwardly toward the smaller end of the kite, the various parts of the kite may easily collapse into a small compass for storage or shipment.

The invention having been set forth, what is claimed is:

A kite, comprising a frame composed of a central longitudinal stay, a transverse stay, a covering for said frame, strands in the margin of said covering and connecting the remote ends of both stays, said transverse stay comprising sections, and means comprising an elongated plate slidable on the central longitudinal stay and to which the sections are pivotally connected, spaced loop members encircling said longitudinal stay and connected to said plate, whereby upon moving said plate in one direction on the longitudinal central stay the frame may be collapsed, and means on the longitudinal central stay for limiting the slidable plate in the other direction on the central longitudinal stay, and a strand connecting the remote ends of the sections of the transverse stay and being drawn taut for bowing the transverse stay, and a bridle and kite cord connected to the kite.

JOHN F. NEARY.
